Maximilian C. Meyer

By his Attorneys Darby & Darby.

UNITED STATES PATENT OFFICE

MAXIMILIAN C. MEYER, OF BROOKLYN, NEW YORK, ASSIGNOR TO JOSEPH H. MEYER BROTHERS, OF BROOKLYN, NEW YORK, A CORPORATION OF NEW YORK

ARTICLE OF JEWELRY

Application filed March 7, 1928. Serial No. 259,625.

This invention relates in general to articles of jewelry and more particularly to earrings.

One of the objects of this invention is the provision of an earring which is exceedingly simple in construction, adapted to cheap and rapid manufacture, and of a rugged construction.

Another object of this invention is the provision of an earring which fits onto the lobe of the ear so as to lie snugly thereagainst without metal parts in contact with the lobe of the ear.

A still further object of this invention is the provision of a spring support to which the ear ornaments are attached so that the whole structure may be frictionally secured to the ear in a manner to prevent irritation thereof.

A still further object of this invention is the provision of an earring which has no screws for securing it to the ear and no exposed wires or portions in which the hair may be caught.

These and other objects, as will appear from the following disclosure, are secured by means of this invention.

This invention resides substantially in the combination, arrangement and relative location of parts, all as will be more fully disclosed hereinafter.

Referring to the drawings—

Figure 1 is a side elevational view of the device;

Fig. 2 is a vertical sectional view of the arrangement of Fig. 1 taken on the line 2—2 of Fig. 1;

Fig. 3 is a vertical sectional view of the device taken on the line 3—3 of Fig. 2;

Fig. 4 is a vertical sectional view similar to that of Fig. 3 of the whole structure showing the spring member separated from the ornaments;

Fig. 5 is a side elevational view with a portion broken away of a modified arrangement showing the ear lobe in dotted lines;

Fig. 6 is an end elevational view of the ornament used in the modified form; and

Fig. 7 is a perspective view of the spring to which the ornaments are attached.

50 Referring to the drawings for a detailed

description, the device is shown comprising two ornaments 1, 1 of any suitable size, shape and color supported on a U-shaped spring member 2. The ornaments 1 have small holes bored in from under in which are secured the small internally threaded tubes 4. The U-shaped spring member 2 is threaded for a short distance at each end, as shown at 3. The ornament may be constructed, for instance of a fusible enamel and then covered with a suitable number of coats or films of pearl lacquer. In assembling the device the U-shaped member 2 consists of a straight rod threaded at each end. The ornaments 1 are screwed thereon tightly so as not to readily become loose. The rod may then be formed into the U-shape form shown in the figures.

In the modified form the ear ornaments 10, 10 are provided with holes extending a short distance therein in which the U-shaped spring member 11 is secured by means of wax or other suitable cement 13. The holes for the ear ornament 10 are indicated at 12 in Fig. 6. The spring 11 is curved at its free ends slightly so that when the earring is being worn the spring 11 will tend to cause the ornaments to grip the ear. Both devices are secured to the ear lobe as indicated in Fig. 5 in which the ear lobe is held between the two ornaments by reason of the friction therewith caused by the spring support.

From the foregoing description it will be apparent that the device is very simple in construction presenting a neat and ornamental effect. In view of the relatively larger area of contact of the ornaments with each side of the ear lobe the earring does not cause irritation and yet firmly grips the ear lobe so as not to be easily displaced.

It will be apparent from the foregoing description that devices employing the principles of this invention may assume numerous forms and I do not, therefore, desire to be particularly limited to the forms shown for purposes of disclosure but rather to the invention as it is defined in the appended claims.

What I seek to secure by United States Letters Patent is:—

1. In an earring, the combination with two

recessed lenticular ornaments, each of said ornaments having an outer surface thereof flattened, of threaded tubes securely mounted in said recesses in said ornaments, a rounded **U**-shaped spring member having threaded ends to provide threaded attachment of said member to said ornaments and to permit of such disposition of said ornaments that the respective flattened portions of the surfaces of each **10** of said ornaments face each other in spaced apart relation and are adapted to come together and frictionally hold therebetween the lobe of the ear of the wearer of such ornament.

15 2. In an earring, the combination with two lenticular shaped ornaments, each of said ornaments having a rectangular shaped recess therein, and a portion of the outer surface thereof flattened, a rectangular **U**-shaped **20** flattened spring member having ends adapted to attachment to said ornaments by insertion in said rectangular shaped recesses, means securing such rectangular **U**-shaped spring member to said ornaments to permit of such **25** disposition of said ornaments that the respective flattened portions of the surfaces of each of said ornaments face each other in spaced apart relation and are adapted to frictionally hold therebetween the lobe of the ear of the **30** wearer.

35 3. In an earring, the combination with two recessed lenticular ornaments, each of said ornaments having an outer surface thereof flattened, of a **U**-shaped spring member having its free ends secured within said recesses to provide attachment of the member to the ornaments and to permit of such disposition of the ornaments that the respective flattened portions of the surfaces of each of said **40** ornaments face each other in spaced relation so that they can frictionally engage the lobe of the ear of the wearer therebetween.

In testimony whereof I have hereunto set my hand on this 23rd day of February, A. D. **45** 1928.

MAXIMILIAN C. MEYER.
